UNITED STATES PATENT OFFICE.

PERCY A. MARTIN, OF COLUMBIA, MISSOURI.

WRENCH.

1,209,002.

Specification of Letters Patent. Patented Dec. 19, 1916.

Application filed August 26, 1914. Serial No. 858,703.

To all whom it may concern:

Be it known that I, PERCY A. MARTIN, a citizen of the United States, residing at Columbia, in the county of Boone and State of Missouri, have invented new and useful Improvements in Wrenches, of which the following is a specification.

The present invention relates to improvements in wrenches, and particularly to the peculiar construction of frame and carriage for combining a monkey wrench and a Stillson wrench, and the primary object of the invention is to provide a device of this class which shall be simple, cheap and efficient.

With the above and other objects in view, the improvement resides in the construction, combination and arrangement of parts set forth in the following specification and falling within the scope of the appended claim.

In the drawing: Figure 1 is a view of a wrench constructed in accordance with the present invention, and Fig. 2 is a perspective view of the frame or carriage.

Referring now to the drawing in detail, the numeral 1 designates the wrench in its entirety. The wrench includes a shank 2 which has its opposite edges provided with threads 3 and 4 respectively. The shank 2 is further provided at one of its ends with laterally extending jaws 5 and 6 respectively, the jaw 5 having an inner smooth working face, while the jaw 6 is provided with a toothed working face.

The movable member or carriage is indicated by the numeral 7. The carriage has one of its corners formed to provide a jaw or head 8 that is adapted to co-act with the jaw 5. The carriage comprises a frame constructed to provide rectangular arms 8^a—8^c extending from and in a line with the active face or sides of the head or jaw 8. The head, from the inactive face thereof, is formed with a flat angular extension 8^b.

Formed with and extending angularly from the flange 8^b, in a line parallel to the plane of the arms 8^a are rectangular members or arms 8^c which are of a greater length than the arms 8^a and which are connected by a transverse member 13. The arms 8^a and 8^c are connected by integral members 8^d, and the arms 8^c, at their juncture with the members 8^d are connected by a transverse member or plate 8^e. By this arrangement it will be noted that a substantially rectangular pocket is provided between the arms

8^a, the plate 8^e and the flange 8^b, while the outer ends of the arms with their connecting portion 13 are disposed in the form of a U-shaped element or yoke. Passing transversely through the ends of the arms 8^a is a pivot 10 whereby the shank 12 of an auxiliary jaw member 11 is connected with the frame, while secured to the transverse connecting wall 8^e of the said frame is a flat spring 14 which depends outwardly from the said frame and contacts with one of the edges of the shank 12 of the jaw 11. Likewise secured to the connecting member 13 at the yoke end of the arms 8^c is a flat spring 15 which projects in an opposite direction from the spring 14 and which contacts with the side of the shank 12 opposite that contacted by the said spring 14. By this arrangement it will be noted that the springs normally sustain the shank 12 and consequently the head 11 thereof normally in one position with relation to the frame. The shank 2 is, of course, adapted to be passed through the space between the arms 8^a and the arms 8^c while the substantially rectangular opening in the sides of the frame of the carriage, receives the operating nut 9 which engages with the teeth or threads 3 and 4 on the shank 2, the said nut being preferably provided with a rounded periphery which is milled as illustrated in Fig. 1 of the drawing.

From the above description, taken in connection with the accompanying drawings, the simplicity of the device as well as the advantages thereof will, it is thought, be perfectly apparent to those skilled in the art to which such invention appertains without further detailed description.

Having thus described the invention, what I claim is:

In combination with a stationary jaw having a centrally arranged angularly disposed toothed shank, of the herein described construction of movable members for the jaw of the said shank, comprising a frame, including a movable jaw having spaced arms extending longitudinally therefrom, an angular member arranged outwardly of the said arms and connected with the jaw, arms formed on the end of said angular member and extending longitudinally therefrom in a direction parallel to the plane of the first mentioned arms, said last mentioned arms being of a greater length than the first mentioned arms and having their

ends connected, a connecting member between the ends of the first mentioned arms and the second mentioned arms, a transverse plate connecting the second mentioned arms 5 at the juncture of the connecting members between the first and second mentioned arms, the toothed shank of the stationary jaw being disposed in the spaces between the first mentioned and second mentioned 10 arms, an operating nut upon the threaded shank and having its opposite sides projecting through the openings in the sides of the frame, an auxiliary jaw including a shank pivotally connected to the ends of

the first mentioned arms, and spring elements secured to the outer and inner connecting members of the second mentioned arms and extending in opposite directions therefrom and contacting with the opposite edges of the shank of the auxiliary jaw. 15

20 In testimony whereof I affix my signature in presence of witnesses.

PERCY A. MARTIN.
